United States Patent Office.

L. J. MARCY, OF NEWPORT, RHODE ISLAND.

Letters Patent No. 97,419, dated November 30, 1869.

PHOTOGRAPHIC PRINTING-APPARATUS.

The Schedule referred to in these Letters Patent and making part of the same.

To all whom it may concern:

Be it known that I, L. J. MARCY, of Newport, in the county of Newport, and State of Rhode Island, have invented a new and improved Photographic Printing-Apparatus; and I do hereby declare that the following is a full, clear, and exact description thereof, which will enable others skilled in the art to make and use the same, reference being had to the accompanying drawings, forming part of this specification, in which—

Figure 1 represents a vertical longitudinal section of my improved photographic printing-apparatus.

Figure 2 is an end elevation of the same.

Figure 3 is a plan or top view of the lamp arranged therein.

Similar letters of reference indicate corresponding parts.

This invention relates to a new instrument for printing photographic pictures, or, more particularly, transparencies, by the aid of artificial light. Such plates are used as slides for magic-lanterns and other purposes.

The invention consists of a lamp of novel construction, placed into a frame or case, so that the light will be projected toward the negative through a narrow aperture of the case.

The invention consists, also, in the general arrangement and construction of the aforesaid case or frame.

A, in the drawing, represents the lamp used in my improved printing-apparatus.

This lamp is made of sheet-metal or other suitable material, of suitable form and size, and is provided with a wick-tube, a, of comparatively great width, so that a wick about four inches wide can be accommodated in the same.

The wick-tube is slightly curved, as shown in fig. 3, so that the flame will be broader than the mere thickness of the wick, for the purpose of avoiding the shadow always seen at the edge of a flat flame.

To the sides of the lamp are secured outward-projecting inclined perforated plates b b, which serve to break the air-currents, and to thereby produce a steady flame.

This lamp A is placed within a sheet-metal or other case, B, which is of suitable form, preferably but little longer than the lamp.

Directly above the wick-tube of the lamp is arranged, across the case B, a horizontal diaphragm, c, which is slotted, to allow the wick to pass through it. The slot is curved similar to the wick-tube.

Both or one of the ends of the case, B, are provided with apertures, adapted to receive perforated slides O C. The aperture in each slide is as large as

required for every particular case, but should not be wider than the thickness of the flame, so that a solid column of light will be behind it.

The rays of light are projected through the perforated slide upon a negative, D, which is placed in front of the plate E, that is to receive the impression.

The plates D E are secured in a suitable frame, F, by means of springs f or other devices, and are held a small distance apart by means of metal plates e e, interposed between their corners.

If the plates D E were placed close together, a well-defined, sharp copy would be produced. If they were placed some distance apart, the copy would, by an ordinary light, become blurred and indistinct. But as, in my case, the light passes through the small aperture of the slide, the rays are not caused to diverge, but are kept together, and are, therefore, passed through the negative in almost parallel direction. The copy will, consequently, be as clear, for all practical purposes, as one produced by ordinary light, with direct contact.

The extent of the illuminated portion of the negative is regulated partly by the distance of the lamp from the negative, partly by the size of the aperture in the slide. The slide is, therefore, made removable, so that another, with a different-sized aperture, may be put in its place.

Having thus described my invention, I claim as new, and desire to secure by Letters Patent—

1. A photographic printing-apparatus, consisting of a lamp and printing-frame, arranged and operating together substantially as described.

2. The lamp A, provided with a curved wick-tube, substantially as and for the purpose described.

3. The case B of the lamp, when provided with a slotted diaphragm, substantially as herein shown and described.

4. The inclined perforated plates b b, formed on the lamp, for the purpose of steadyng the flame, as set forth.

5. The changeable perforated slides C, or their equivalent, arranged and operating substantially as and for the purpose herein shown and described.

6. The printing-frame F, made substantially as described, to carry the negative and the sensitive plate, as described.

L. J. MARCY.
